UNITED STATES PATENT OFFICE

160,492

AUTOMOBILE

Felix Grafton, Los Angeles, Calif.

Application April 3, 1950, Serial No. 8,936

Term of patent 3½ years

(Cl. D14—3)

To all whom it may concern:

Be it known that I, Felix Grafton, a citizen of the United States, residing at Los Angeles, in the county of Los Angeles and State of California, have invented a new, original, and ornamental Design for an Automobile, of which the following is a specification, reference being had to the accompanying drawing, forming part thereof.

Figure 1 is a perspective view of an automobile, showing my new design.

Figure 2 is a top plan view thereof on a reduced scale; and

Figure 3 is a rear elevational view thereof on a reduced scale.

I claim:

The ornamental design for an automobile, as shown.

FELIX GRAFTON.
